UNITED STATES PATENT OFFICE.

JOSEF KLEIN, OF NEW YORK, N. Y.

SCAFFOLD AND FIRE-ESCAPE.

SPECIFICATION forming part of Letters Patent No. 292,221, dated January 22, 1884.

Application filed November 9, 1883. (No model.)

To all whom it may concern:

Be it known that I, JOSEF KLEIN, of the city, county, and State of New York, have invented certain new and useful Improvements 5 in Scaffolds and Fire-Escapes, of which the following is a specification.

This invention has reference to an improved scaffold and fire-escape for hotels, factories, tenement-houses, and other buildings, which 10 is intended to be used for the double purpose of serving as a scaffold for painting or cleaning the exterior wall of the building, washing windows, &c., and as a fire-escape in case of danger; and the invention consists of a scaffold 15 that is suspended by ropes from horizontal rack-bars that are guided on strong posts of the roof of the building and moved forward or back with the scaffold by pinions meshing with the teeth of the rack-bars. The suspension-ropes are guided in hook-eyes sliding on 20 fixed arms arranged below the cornice of the building and applied to drums at both ends of the scaffold, which drums are simultaneously operated by a transmitting-shaft and bevel-gears from a hand-crank provided with ratchet-and-pawl mechanism, and located centrally 25 between the winding-drums.

In the accompanying drawings, Figure 1 represents a front elevation of a building with 30 my improved scaffold and fire-escape arranged on the roof of the same. Fig. 2 is a vertical transverse section of the building, showing my improved scaffold and fire-escape lowered for use. Figs. 3, 4, and 5 are respectively a 35 front view, an end view, and a detail of the hoisting mechanism of the scaffold; and Fig. 6 is a detail of the sliding hook-eyes for guiding the suspension-ropes of the scaffold.

Similar letters of reference indicate corresponding parts.

A in the drawings represents a scaffold of any approved construction, which is provided at the ends with upright posts B B, that are rigidly secured to the platform or bottom of 45 the scaffold A, and provided with bearings for the transverse shafts C C of the drums C, that are keyed thereto midway between the upright posts B B. The suspension-cords D D are applied to the drums and wound or unwound therefrom by means of a longitudinal shaft, a, that turns in bearings of the posts B B, and is provided near its center and its end

with bevel-wheels a', of which the central one meshes with the bevel-gear a'', that is revolved by a hand-crank, a'', keyed to the shafts of the 55 bevel-gear a'', while the outer bevel-wheels, a', mesh with bevel-gears a' of the drum-shafts C and impart revolving motion in one or the opposite direction thereto. A ratchet-wheel, a'', is placed on the shaft of the crank a'' and 60 locked by a pawl, a'', as shown in Figs. 3 and 5. By turning the hand-crank a'', the suspension-ropes D D are either wound on the drums C or unwound therefrom, according as the scaffold is desired to be raised or lowered. 65 By the transmitting-shaft and bevel-wheels shown a scaffold of considerable size may be raised or lowered without difficulty by a single person standing at the center of the platform. The suspension-ropes D D are guided 70 in hook-eyes D' at the ends of horizontal rods, which are guided by means of sleeves on fixed arms D'', secured to the wall of the building, below the cornice, whereby the scaffold, when suspended, is kept at the required distance 75 from the wall. The suspended ropes D are applied at their upper ends to horizontal rack-bars, E, that are supported in fixed upright posts F, secured to the roof by braces F' and fastening-rods F'' at such a distance from the 80 cornice that sufficient room for the scaffold is provided in front of the upright posts F. The rack-bars E are guided along forward-extending supporting bracket-rods E' and moved forward or back on the same by pinions E'', 85 which mesh with the teeth of the rack-bars E. The pinions E'' are operated by a longitudinal connecting-shaft, e, that turns in bearings of the posts F, and is provided at one or both ends with a hand-crank, e''. By turning the 90 pinion-shaft e in one direction, the rack-bars E are moved forward, so as to extend beyond the cornice of the building, while by turning the pinion-shaft in the opposite direction the rack-bars are moved back toward the posts F. 95 When the scaffold has been raised above the level of the cornice of the building, it is moved inwardly by the rack-bars and secured in position on the roof in front of the posts.

To facilitate the motion of the scaffold, it is 100 provided with bottom rollers, f, as shown in Fig. 4.

When the scaffold is desired to be used for painting the exterior of the building, or for

cleaning the windows, or as a fire-escape in case of danger, it is lowered by first moving the horizontal rack-bars E and the scaffold to such an extent that the latter clears the cornice of the building. The person using the scaffold then gets into it and lowers the same by unwinding the suspension-ropes D from the drums C by turning the hand-crank a^2 . When below the cornice, the suspension-ropes are placed into the hook-eyes, which are then drawn out to their full length, so as to keep the scaffold at such a distance from the walls that it moves clear of the window-sills and other projections of the same.

15 The scaffold can be raised or lowered by one person without difficulty, and can be used as such or as a fire-escape, as required.

Having thus described my invention, I claim as new and desire to secure by Letters Patent—

20 1. The combination of a scaffold provided with winding-drums at its ends, means for actuating the same, suspension-ropes applied to said drums, horizontal rack-bars to which the upper ends of the suspension-ropes are at-

tached, standards secured to the roof of the building for supporting and guiding the rack-bars, and means for moving the rack-bars and scaffold forward and backward, substantially as and for the purpose set forth.

2. The combination of a scaffold provided with winding-drums at its ends, means for operating said drums, suspension-ropes applied to said drums, hook-eyes for the ropes, applied by guide-sleeves to fixed rods below the cornice, horizontal rack-bars to which the upper ends of the suspension-ropes are attached, upright posts secured rigidly to the roof, for supporting and guiding the rack-bars, and means for moving the rack-bars and scaffold forward or back, substantially as specified.

In testimony that I claim the foregoing as my invention I have signed my name in presence of two subscribing witnesses.

JOSEF KLEIN.
